UNITED STATES PATENT OFFICE.

WALTER STANLEY, OF CHICAGO, ILLINOIS.

DRAIN.

1,194,088.

specification of Letters Patent. Patented Aug. 8, 1916.

Application filed March 20, 1916. Serial No. 85,511.

To all whom it may concern:

Be it known that I, WALTER STANLEY, a citizen of the United States, residing at Chicago, in the county of Cook and State of Illinois, have invented certain new and useful Improvements in Drains, of which the following is a specification.

The present invention has to do with improvements in drains for ice boxes and the like, but an examination of the construction herein disclosed will show that it is not limited to this particular class of service. For purposes of convenience in illustration, however, I have shown the drain as applied to 15 an ice box.

It is customary in the construction of ice boxes to provide them with drip pipes for the delivery of the water occasioned by the melting of the ice, and such drip pipes usually extend down from the bottom portion 20 of the ice boxes. It is also customary in the construction of apartment buildings and the like to provide permanent drain pipes at suitable locations in the kitchens, said drain pipes being for the reception of the water as 25 it drips from the ice boxes. It is very often found that, when the ice box is set in position, its drip pipe does not properly register with the drain fixture, and as a result the 30 water dripping from the ice box finds its way onto the floor. Furthermore, when the position of the drain has been established in the floor of the building, the same cannot be readily changed so as to register up with 35 other form or size of ice box which may be used in place of the one for which the 40 fixture was originally installed.

One of the objects of the invention is to provide a drain suitable for this class of 45 service, which drain is so constructed that it may be readily adjusted to receive the drip water from different positions with respect to the fixed drain pipe, to thereby give great flexibility in establishing the position of the 50 drain fixture itself. This will enable the user to position the fixture at any point desired according to the exact position of the drip pipe of the ice box.

In this connection another object of the 55 invention is to so construct the parts that the aforementioned flexibility of adjustment may be secured with a drain fixture of minimum size and cost.

Another object of the invention is to so 60 construct the fixture that it may be delivered in knock-down condition and may be

very easily and readily assembled at the point of use or installation.

Other objects and uses of the invention will appear from a detailed description of 65 the same which consists in the features of construction and combinations of parts hereinafter described and claimed.

In the drawing: Figure 1 shows a front elevation of the lower portion of the ice box, a portion of the base of the same being broken away so as to reveal the position of the drip pipe; Fig. 2 shows a vertical section through the fixture embodying the features of the present invention, being taken on the line 3—3 of Fig. 3, looking in the direction of the arrows; and Fig. 3 shows a plan view of the fixture itself, showing in dotted lines an adjusted position of the spout.

The ice box 4 is provided with the drain pipe 5 in the usual manner. Installed in the floor of the building is the pipe 6 which is supposed to register with the drip pipe 5 when the ice box stands in the position assigned to it. However, in the position of the ice box shown in Fig. 1, the drip pipe 5 does not register with the pipe 6, and, therefore, recourse is had to the drain fixture to which the present invention relates. 85

On the upper end of the pipe 6 is connected a circular bowl-shaped fixture 7 of a diameter sufficient to receive drippage from the drain pipe 5 within a variation of positions of the ice box such as would usually 90 be found in service. An inverted cup or the like 8 may be placed within the bowl 7 and above the upper end of the pipe 6, said cup being provided with a number of notches or recesses 9 around the lower portion of its 95 periphery so as to permit the water to pass into the pipe. Formed in one side of the bowl 7 is a notch or opening 10 adapted to receive a spout or the like 11. Said spout is elongated in form, its floor 12 tapering 100 from the end 13 to the end 14. The outer lower surface of the spout 11 conforms in contour throughout its length substantially to the contour of the notch or opening 10, so that the parts will fit together properly 105 in any adjusted position of the spout. The drippage falling upon the floor of the spout at any point throughout its length will run down and be delivered into the bowl 7.

Means are provided for connecting the 110 spout to the bowl at any desired position of adjustment. In the particular construction

illustrated, said means takes the form of one or more holes 15 formed in the body of the bowl and adapted to receive pins or the like 16 on the lower face of the spout. The position of the spout may be readily adjusted by setting it at the desired position, then compressing the proper pin or pins down into the hole or holes 15. An examination of Fig. 3 shows the presence of two sets or rows 10 of the pins 16. These, of course, register up with two similar holes 15, and when this construction is adopted, the spout will be rigidly held against twisting or turning with respect to the bowl. I desire to point out, 15 however, as far as the feature of adjustment of the spout is concerned, a greater or less number of rows of pins may be used, or for that matter any other suitable form of attachment may be used in place of the pins 20 and holes.

The manner of installing and using the invention will be readily apparent to those skilled in the art. I desire to point out, however, that by the use of an adjustable 25 spout, as is herein disclosed, the drippage may be collected from any position of the ice box drain within a radius of the pipe 6, which radius is only limited by the length of the spout itself and the size of the bowl 7. 30 I desire, furthermore, to point out that the foregoing result may be accomplished even when the bowl is of very small size and the spout of small width. The adjustment of the spout back and forth will, however, be limited to a position such that the drippage 35 flowing from it will be properly delivered into the bowl. In order to set the spout into different radial positions, the bowl may be turned about the pipe 6 as a center in either 40 direction.

While I have herein shown and described only a single embodiment of my invention, still it will be understood that I am in no wise limited to said embodiment, except as 45 I may limit myself in the claims.

I claim:

1. In a device of the class described, the combination of a circular bowl having a central drain opening and a recess in its side

wall, there being a pair of vertical openings 50 in the side wall at the said recess, an elongated spout adapted to drain into the bowl and having its under surface of contour complementary to the contour of the recess, and a plurality of pairs of downwardly 55 projecting lugs on the lower face of the spout, the lugs of each pair being suitably spaced for simultaneous entry into the aforesaid openings, whereby the spout may be set in any desired position of adjustment with 60 respect to the bowl, substantially as described.

2. In a device of the class described, the combination of a bowl having a drain opening and having a peripheral notch, there being an opening in the bowl at the position of the notch, an elongated spout adapted to drain into the bowl and having its lower surface of contour complementary to the contour of the notch, and a plurality of 70 lugs on the lower portion of the spout, each lug being adapted for entry into the aforesaid opening, whereby the spout may be set into different adjusted positions with respect to the bowl, substantially as described. 75

3. In a device of the class described, the combination of a bowl having a peripheral recess, an elongated spout adapted to drain into the bowl and having its lower portion of contour complementary to that of the recess, and a plurality of lugs on the lower portion of the spout adapted for engagement with the bowl for the purpose of securing the spout in any desired position of adjustment with respect to the bowl, substantially 80 as described. 85

4. In a device of the class described, the combination of a bowl, an elongated spout adapted to drain into the bowl, said spout being adjustable with respect to the bowl 90 longitudinally of its length, and means for securing the spout to the bowl in any desired adjusted position, substantially as described.

WALTER STANLEY.
